BODY AND SHOULDER BRACE

Filed Feb. 5, 1925

Fig. 1.

Diagram of a pen nib assembly labeled 'Fig. 2.' The diagram shows a central tube with a pointed tip. Numbered callouts point to various parts: '1' points to the tip, '2' points to the main body, '3' points to a slot on the side, and '1'' points to a small hole near the tip.

INVENTOR
Elwin T. Davison,
Attleboro,
His ATTORNEY.

UNITED STATES PATENT OFFICE.

ELWIN T. DAVISON, OF ATHENIA, NEW JERSEY.

BODY AND SHOULDER BRACE.

Application filed February 5, 1925. Serial No. 6,998.

To all whom it may concern:

Be it known that I, ELWIN T. DAVISON, a citizen of the United States, and a resident of Athenia, in the county of Passaic and 5 State of New Jersey, have invented new and useful Improvements in Body and Shoulder Braces, of which the following is a specification.

This invention relates to body and shoulder braces and has for its particular objects 10 the provision of a device that is comfortable to the user, effective for automatically correcting the posture and durable when in constant use.

15 I am aware that heretofore numerous corrective devices have been devised, but none so far as I am aware possess the novel features embodied in my improved brace and consequently were incapable of accomplishing 20 the same results.

My invention is fully set forth in the following detailed description and drawings forming a part of this specification in which—

25 Figure 1 is an elevation of my improved brace showing the same in position on the user; and

Fig. 2 is a transverse section along the lines 2—2 of Fig. 1.

30 Referring to the drawings and the construction shown therein, the reference numerals, 1, 1' designate the rear and front members respectively of a back-support member or pad formed of "coutil cloth" or 35 other tough fabric, the same being stiffened with lateral and central stays 2 and 3 respectively, of whale bone or the like.

At the top and bottom of said support member, I provide loops *a*, *a'* within which 40 are secured links *b*, *b'* of plates *c*, *c'*, each of said plates is provided with two end pins 4 and 5 respectively and central pins 6, which pins serve to pivotally secure metallic traveler members 4', 5' and 6' to said support 45 member.

Shoulder straps 7, 7' are firmly secured or anchored at their rear ends to the said back support, the straps being so located that their lower edges at the point of juncture 50 with said support substantially coincide with the transverse median line of the support. Said straps are secured at their upper ends to links 8, 8' which are connected by pins or pivots 9, 9' with traveler members 10, 10'. 55 Suitable buckles 11, 11' permit of the ad-

justment of the length of the strap 7, 7' respectively.

An abdominal strap or band comprising two members 12, 12' adapted to be buckled together is secured at its respective ends to 60 links 13, 13' which are in turn connected by pins 14, 14' to travelers 15, 15'.

A single continuous compensating cable or evener member *d*, preferably of stout cord, is reeved through the travelers carried 65 by the back support and the shoulder straps and abdominal band respectively in the manner illustrated.

The brace is fitted to the body of the wearer in the manner shown and adjusted 70 so that a slight steady, but almost imperceptible tension is exerted by the shoulder straps and abdominal band. When so adjusted, the brace is not only comfortable, but extremely effective for correcting round 75 shoulders and the posture generally so that one instinctively assumes a correct posture. Furthermore, owing to the freedom of movement permitted by the evener cords, as well as the location and manner of securing the 80 shoulder straps and abdominal band thereto, the wearer can participate in all kinds of vigorous exercises and athletic events without necessitating the removal of the brace 85 or experiencing any discomfort when the same is so worn. In this particular respect 90 my brace possesses highly important advantages over prior structures in that the growing youth is not disposed to discard it during his or her participation in the athletic 95 events, at which time it may be of the utmost importance to the particular individual that the brace should be worn in order to exert a steady corrective influence upon the 100 posture of the wearer.

The shoulder straps 7, 7' are preferably formed of elastic webbing and the portion of the abdominal straps which is adjacent the ends carrying the links 13, 13' are also 105 preferably formed of double elastic webbing, the same extending approximately one-third of the length of each of such abdominal straps, whereas the remainder of each of such abdominal straps or bands is formed of plain inelastic webbing.

The functioning of the evener cord, as stated, to automatically compensate and distribute throughout the device any tension exerted by unduly tightening either one or both of the shoulder straps or the abdominal 110

band, although preferably the shoulder straps are adjusted by means of the buckles 11, 11' so as to be approximately of the same length.

5 Various modifications may be made in the construction herein described without departing from the spirit of my invention as set forth in and covered by the appended claims.

10 Having thus described my invention, what I claim and desire to obtain by Letters Patent of the United States is:

1. In a brace of the character described, the combination comprising a pad support, 15 flexible means for stiffening the same longitudinally, means for positioning the said support on the back of a wearer including a plurality of shoulder straps, each of said straps being anchored by one of its ends directly to said pad support, and the other end of each strap being secured to said support and being capable of automatic adjustment with respect thereto, an abdominal band and 20 equalizer means interconnecting the free ends of said shoulder straps and the abdominal band with said support, whereby the said brace automatically accommodates itself to body movements.

2. In a brace of the character specified, 25 a pad support member adapted to fit the back of a wearer, abdominal bands each having one end permanently secured to said pad support at points adjacent the bottom thereof, means for holding the support in position on the back of a wearer, including a plurality of straps adapted to embrace the body of the wearer, each permanently se-

cured at one of its ends to said support at a point intermediate the top and bottom of the latter, and the other ends of said straps 40 being adjustably secured to said support and being free to move with respect to said support and equalizer means interconnecting one of the ends of each of said straps, said bands and said support.

3. In a brace of the character specified, a pad support member provided with longitudinal stiffening stays, a plurality of traveler members pivotally secured to the said support adjacent the top and bottom thereof, a plurality of shoulder straps each permanently secured at one of its ends to said support at points adjacent the middle of said support from the top to bottom thereof and the other ends of said straps each being 55 provided with a traveler member, pivotally secured thereto, abdominal bands, each of the same having a traveler member pivotally secured to one of its ends, and a continuous evener cord reeved successively and alternately through traveler members secured to the shoulder straps and traveler members secured to the top of said support and thence reeved through a traveler member secured to the bottom of said support and thence 60 alternately reeved through traveler members secured to the abdominal bands and thence through another traveler member secured to the bottom of said support.

Signed at New York, in the county of New 70 York and State of New York, this 4th day of February, 1925.

ELWIN T. DAVISON.
